UNITED STATES PATENT OFFICE

JOHN H. DUNCAN, OF SALEM, OREGON, ASSIGNOR OF ONE-HALF TO LAKE W. PRICE, OF SALEM, OREGON

ROOFING SHINGLE

Application filed August 5, 1930. Serial No. 473,135.

This invention relates to roofing shingles, and more particularly to shingles of that type made of flexible water-proof material and adapted to be laid in overlapped interlocking 5 courses.

The invention has for one of its objects to provide shingles of the character stated wherein the interlocking connection between the shingles of adjacent courses thereof shall 10 be such as to positively prevent the separation of the shingles by the wind, and wherein the means through the medium of which the interlocking connection between adjacent courses is established shall be such as to present a roof of pleasing appearance.

The invention has for a further object to provide shingles of the character stated wherein the means through the medium of which the interlocking connection between adjacent 20 courses is established shall be such as to permit the interlocking connection to be easily and quickly effected and such as to permit the shingles to be manufactured at a comparatively low cost and with comparatively little or 25 no waste.

With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a plan view of a fragmentary portion of a roof constructed from shingles embodying my invention;

Figure 2 is a plan view of one unit of the shingles;

Figure 3 is a plan view of another unit of the shingles;

Figure 4 is a plan view of a still further unit of the shingles;

Figures 5 is a sectional view taken on the plane indicated by the line 5—5 of Figure 1, and

Figure 6 is a sectional view taken on the plane indicated by the line 6—6 of Figure 1.

A roof constructed in accordance with my invention consists of courses of shingles A, a course of shingles B, and a course of shingles C, all of which may be made from

any well known or appropriate flexible water-proof material.

Each of the shingles A consists of a body 1 of elongated rectangular formation in contour, and tabs 2 extending downwardly from the lower edge of the body and of substantially triangular formation in contour. The tabs 2 are provided near the body 1 with notches 5 which extend upwardly from the side edges 3 of the tabs. The tabs 2 are provided below the notches 5 with slits 6 and 6^a, the slits 6 extending inwardly and downwardly from the side edges 3 of the tabs, and the slits 6^a extending downwardly and inwardly from the lower ends of the slits 6. 55 The slits 6 and 6^a provide tongues 7 which are provided at their upper edges and near the lower or attached ends with shoulders 7^a and which taper from their shoulders in the direction of their free or upper ends. 60

Each of the shingles B consists of a body 8 of elongated rectangular formation in contour, and tabs 9 extending downwardly from the lower edge of the body and of substantially triangular formation, in contour. The 70

tabs 9 are provided near the body 8 with notches 11 which extend upwardly from the side edges 10 of the tabs 9. The tabs 9 are provided below the notches 11 with slits 11^a and 11^c, the slits 11^a extending inwardly and downwardly from the side edges 10 of the tabs 9, and the slits 11^c extending downwardly and inwardly from the lower ends of the slits 11^a. The slits 11^a and 11^c provide tongues 11^b which are provided at their upper edges and near their lower or attached ends with shoulders 11^d and which taper from the shoulders in the direction of their free or upper ends. 85

Each of the shingles C is similar to the 90 shingles A with the exception that the tabs 2^a thereof project upwardly from the upper edge of the body 1^a thereof.

In practice, a course of the shingles C is first applied to the roof of a building, and the shingles of this or the starting course are nailed to the roof at the points indicated by 95 12. A course of the shingles B is then applied with their bodies 8 and tabs 9 overlapping the tabs 2^a and bodies 1^a, respectively, of 100

the shingles C. The lower ends of the tabs 9 are straight, as shown at 9^a, and such ends are arranged in alignment with the lower edges of the bodies 1^a. The shingles B are 5 secured to the roof at the points indicated by 13.

A course of the shingles A is then applied with the lower portions of their bodies 1 and the upper portions of their tabs 2 overlapping 10 the bodies of the shingles B, and with the lower end portions of their tabs 2 extending across the upper portions of the triangular recesses between the tabs 9 of the shingles B. The bodies 1 of the shingles A are secured to 15 the roof at the points indicated by 14. The tongues 7 pass through the notches 11 and are located below the tabs 9, and the shoulders 7^a of the tongues 7 are located above the notches 11, whereby to establish such interlocking connection between the lower end 20 portions of the tabs 2 and the upper portions of the tabs 9 as to positively prevent the lower ends of the tabs from moving upwardly or curling upwardly. The remaining courses 25 of the roof are made up from the shingles B and A, the shingles B of these courses having truly triangular tabs. The tabs of the shingles of these courses are located in the manner set forth. Furthermore, the shingles 30 are so applied to the roof as to arrange the meeting end edges of the bodies of the shingles of one course out of alignment with the corresponding edges of the shingles of the next upper and lower courses. Due to 35 the fact that the notches of the tabs extend upwardly, the tongues may be readily interlocked with the tabs.

Due to the interlocking connection established between the shingles of the adjacent courses by the notches 5 and 11 and by 40 the tongues 7 and 11^b, the lower ends of the tabs are positively held against separation by the wind. By reference to Figure 1, it will be seen that the shingles are not only connected 45 together in a manner to prevent the separation of the lower ends of the tabs and in a manner to hold such ends from curling upwardly but are also connected in a manner to give the roofing a highly artistic appearance, 50 this being brought about by the peculiar formation of the notches and slits which provide the shingles with what appear to be curved corners. The shingles A and B may be formed from a single strip of roofing material by cutting the strip along a zigzag line 55 and at the same time cutting the strip to form the notches 5 and 11 and the slits 6 and 11^a.

While I have described the principle of 60 the invention, together with the structure which I now consider the preferred embodiment thereof, it is to be understood that the structure shown is merely illustrative and that such changes may be made, when desired, as fall within the scope of the invention as 65 claimed.

I claim:—

1. A shingle of flexible water-proof material, comprising an elongated body, and a plurality of triangular tabs extending downwardly from one edge of the body, the tabs being provided near their upper ends with notches extending upwardly from the side edges of the tabs, the tabs being provided between their lower ends and the notches with slits extending inwardly and downwardly from the side edges of the tabs, and the tabs being provided with slits extending downwardly and inwardly from the lower ends of said first slits, the slits forming tongues provided at their inner edges and near their lower or attached ends with shoulders and tapered from the shoulders in the direction of their upper or free ends. 70 75 80

2. A shingle of flexible water-proof material, comprising an elongated body, and a plurality of triangular tabs extending downwardly from one edge of the body, the tabs being provided near their upper ends with notches extending upwardly from the side edges of the tabs, the tabs being provided between their lower ends and the notches with slits extending inwardly and downwardly from the side edges of the tabs, and the tabs being provided with slits extending downwardly and inwardly from the lower ends of said first slits, the slits forming tongues provided at their inner edges and near their lower or attached ends with shoulders and tapered from the shoulders in the direction of their upper or free ends. 85 90 95 100 105

In testimony whereof I hereunto affix my signature.

JOHN H. DUNCAN.
